United States Patent Office

Des. 199,895
Patented Dec. 29, 1964

199,895

ANIMAL HOUSE

Mark L. Morris, Topeka, Kans., assignor to Mark Morris
Associates, Inc., a corporation of Kansas

Filed June 19, 1963, Ser. No. 75,457

Term of patent 14 years

(Cl. D12—2)

FIG. 1

I claim:

The ornamental design for an animal house, as shown.
